UNITED STATES PATENT OFFICE.

LEOPOLD WOLF, OF NEW YORK, N. Y.

COMBINED TOILET-MIRROR AND PHOTOGRAPHIC ALBUM.

SPECIFICATION forming part of Letters Patent No. 292,884, dated February 5, 1884.

Application filed May 31, 1883. (No model.)

To all whom it may concern:

Be it known that I, LEOPOLD WOLF, of the city, county, and State of New York, have invented certain new and useful Improvements 5 in Combined Toilet-Mirrors and Photograph-Albums, of which the following is a specification.

This invention has reference to an improved combination of toilet-mirror and photograph-album, which are so arranged in connection with each other that an elegant and useful device for the parlor or dressing-room is obtained; and the invention consists of an upright supporting-frame carrying a centrally-pivoted 10 mirror-frame, to the back of which is applied the cover of an axially-turning photographic album of a size equal to the mirror-frame. After the mirror-frame has been reversed, the 15 album is turned into position at right angles to the longitudinal center line of the mirror-frame, so as to be readily opened to exhibit photographs. The centrally-pivoted mirror-frame is locked to the supporting-frame by a locking device of special construction, whether 20 the mirror or photograph-album is exposed at the front part of the same.

In the accompanying drawings, which fully illustrate my invention, Figure 1 represents a perspective view of my combination toilet-mirror and photograph-album. Fig. 1^a is a side elevation. Fig. 1^b is a side elevation, showing the toilet-mirror and photograph-album in the act of being turned in the supporting-frame. Figs. 2 and 3 are perspective 35 views, showing the photograph-album respectively in position ready to be opened and after it has been opened. Fig. 4 is a vertical transverse section on line xx , Fig. 1; and Figs. 5, 6, and 7 are details of the locking device and 40 pivots of the mirror-frame.

Similar letters of reference indicate corresponding parts.

A represents the supporting-frame of my improved combination toilet-mirror and photograph-album, which frame is rigidly secured 45 in a vertical or, preferably, a backwardly-inclined position on a base, A'. The frame A is provided with an oblong opening, which is filled by a panel, B, that is applied by center 50 pivots, dd , to opposite sides of frame A. The pivoted panel B carries at its front a mirror,

B', and at its back a photograph-album, C, that is equal in size, or nearly so, to the panel B. The rear cover of the photograph-album is pivotally attached to the panel B, the pivot 55 mechanism shown in the drawings consisting, preferably, of a disk, b , that is rigidly attached to the back of the rear cover of the album, and provided with a metallic circular flange, b' , the latter extending into an annular guide-groove, 60 b^2 , arranged in the panel B, immediately back of the mirror, as shown clearly in Fig. 4. By means of this connection the album C may be turned at the back of the panel B without wabbling or shaking. When the longitudinal axis 65 of the album is in line with the longitudinal axis of the panel B and supporting-frame A, the album-clasps are located at one side and the back of the album at the other side of the panel; but when the album is turned around its center 70 into position so that its longitudinal axis is at right angles to the longitudinal axis of the panel B and frame A, as shown in Figs. 2 and 3, the album extends across the frame and the clasps are at the upper part, so that when they 75 are opened the album can be opened downwardly, so as to expose the pictures therein, as shown in Fig. 3. In this position the supporting-frame holds both parts of the album in slightly-inclined position, and enables thereby 80 the more convenient inspection of the pictures. After the pictures are inspected, the album is closed again by the clasps and turned into vertical position back of the panel B. The latter is then turned on its pivots through an angle 85 of one hundred and eighty degrees, whereby the mirror is brought to the front of the supporting-frame and the album stored away at the back of the mirror-frame, as shown in Figs. 1 and 1^a.

To hold the album C and panel B rigidly in position in line with the supporting-frame A, the locking device shown in detail in Figs. 5 and 6 is used, which consists of a sliding pivot, d , provided with a button, d' , and with a laterally-extending flat bar, d^2 . The pivot d is guided in a hole of the panel B and a hole of an outer retaining-plate, d^3 , of the supporting-frame A. The laterally-extending bar d^2 is guided in recesses d^4 , d^5 of the frame A and 95 panel B, respectively.

Between the retaining-plate d^3 of frame A

and the laterally-extending bar d^2 is interposed a spiral spring, d^3 , which tends to press the pivot d in downward direction. When it is desired to turn the mirror-panel B, the pivot 5 d , together with its bar d^2 , is raised by its button d' against the tension of the spring d^3 until the bar d^2 clears the recess d^5 of the mirror-panel B. In this position the panel B may be readily turned on its pivots d . When the 10 panel B arrives in line with the main frame A, the button d' is released, so that the spring d^3 presses the bar d^2 into the recess d^5 of the mirror-panel B, and produces thereby the locking of the mirror-panel B to the supporting-frame A. The lower pivot, e , is preferably set by a square or oblong portion, e' , into a socket of the supporting-frame A, as shown in 15 Fig. 7. A spiral spring, e^2 , is arranged around the same, said spring being attached at one end to the pivot e , while its opposite end is laterally extended and attached to the mirror-panel B. This spring e^2 facilitates the turning of the mirror-panel and album in one direction, while the tension of the spring is re-established by the turning of the mirror-frame 20 in the opposite direction. When the locking device on the upper part of the supporting-frame A is raised, the mirror-panel B is released, so that it turns by the action of the 25 spring e^2 of the lower pivot, e , readily around its axis, so as to bring either the mirror or the album to the front of the supporting-frame. When the album is at the front, it is next turned 30 on its center pivot into the position shown in Fig. 2, and then opened, as shown in Fig. 3, so that the pictures can be conveniently looked at.

After the photograph-album has been used, it is closed, turned into upright position, and then turned with the mirror-panel on the pivots d , so that the album will be at the back 40 of the panel and the mirror at the front of the same, the whole forming a very attractive and useful ornament.

Having thus described my invention, I claim as new and desire to secure by Letters Patent— 45

1. The combination, with an upright supporting-frame, of a centrally-pivoted and reversible panel having a mirror at one side and a photograph-album attached at the other side, the album being centrally pivoted to the back of the mirror-panel, substantially as and for the purpose set forth. 50

2. The combination, with an upright supporting-frame, A, of a centrally-pivoted and reversible panel, B, having a mirror at one side and a photograph-album, C, at the other side, the rear cover of said album being connected by a fixed disk, b , having a circular flange, b' , to an annular guide-groove of the mirror-frame, substantially as set forth. 55

3. The combination of the upright supporting-frame A and a centrally-pivoted and reversible mirror-panel, B, with a locking device applied to one of the pivots, said pivot being provided with a laterally-extending locking-bar, d^4 , button d' , and interposed spiral spring, d^3 , the locking-bar being guided in recesses d^4 and d^5 of the supporting-frame and mirror-panel, substantially as described. 60

4. The combination, with an upright supporting-frame, A, of a reversible mirror-panel B, turning on center pivots, d and e , the upper pivot, d , being provided with a spring-pressed locking device, while the lower pivot, e , is provided with a torsion-spring, e^2 , by which the turning of the mirror in the supporting-frame is facilitated when the locking device of the upper pivot, d , is released, substantially as and for the purpose set forth. 70

In testimony that I claim the foregoing as 80 my invention I have signed my name in presence of two subscribing witnesses.

LEOPOLD WOLF.
